UNITED STATES PATENT OFFICE.

FRANCISZEK SZYMANSKI AND PIOTR DUDEK, OF ELLSWORTH, PENNSYLVANIA.

DESIGN FOR A SEALING STAMP.

Application filed June 12, 1922. Serial No. 2,629. Term of patent 3½ years.

To all whom it may concern:

Be it known that we, FRANCISZEK SZYMANSKI and PIOTR DUDEK, citizens of Poland, and residing at Ellsworth, in the county of Washington and State of Pennsylvania, have invented a new, original, and ornamental Design for Sealing Stamp, of which the following is a specification, reference being had to the accompanying drawing, forming a part thereof.

The figure is a front view of my stamp showing my design.

We claim:

The ornamental design for a sealing stamp.

FRANCISZEK SZYMANSKI.
PIOTR DUDEK.
